BUILDING STRIP

Albert E. F. Moone, Chicago, Ill., assignor to
 Lehon Company, Chicago, Ill., a corporation of
 Illinois

Application March 4, 1931. Serial No. 519,987

3 Claims. (Cl. 20—5)

This invention relates to building strips and has been illustrated as embodied in strips of siding intended to present the appearance of a brick wall. According to the invention a continuous web having been saturated with asphalt may be surfaced with a granular material of one color and then printed or painted with a definite design as in imitation of brick outlines, the design being surfaced with another granular material of a different color. In the example shown and described the usual surfacing is with a brick color, such as red, and the design is in black outlining two rows of bricks and providing markers for indicating the proper position for an overlying strip. The strip is cut exactly on the edge of the design so as to give the best appearance when laid.

Several objects are accomplished by this invention, and a strip is provided which not only is cheaper to produce, but also is cheaper to handle and lay than other strips having the same purpose. Former strips made in imitation of bricks have had only one row of bricks with the result that it was necessary to lay twice as many strips in order to cover the roof, even if the strip lengths were the same. According to the present invention, the covering is more durable in spite of using fewer strips because there is a double thickness of material at all points. In the prior practice the vertical lines between the bricks were formed by cutting out that portion of the strip. The result was that although the overlying strip made a second thickness at the position of the brick, there was only one thickness at the position of the cut between the bricks. Strips made in accordance with this invention are stronger than the former strips because there are no downwardly projecting tabs and corners which are obviously more easily caught and bent up or torn off. On account of these advantages it is possible to make a siding of a lighter weight felt than was formerly desirable and still have the finished product more strong and durable than before. According to another feature of the invention, the design includes markers which indicate the proper position for an overlying strip. This not only facilitates and quickens the laying of the strips, but insures a proper appearance of the finished wall.

With these and various other objects in view, the invention may consist of certain novel features of construction and operation, as will be more fully described and particularly pointed out in the specification, drawing and claims appended hereto.

In the drawing, which illustrates an embodiment of the device, and wherein like reference characters are used to designate like parts,

Figure 1 is a view illustrating the web from which the strips are cut;

60

Figure 2 is a plan view of one of the strips;

Figure 3 is a cross-section of Figure 2 taken along the line 3—3; and

Figure 4 is a view illustrating an assembled siding composed of numerous strips such as shown in Figure 2, properly laid in overlapping relation.

Although my invention may take many forms, only one has been chosen for illustration. This is best shown in Figures 2 and 3 showing a single strip 10. This strip comprises a base 12 of felt

70

saturated with asphalt or the like and preferably additionally coated with asphalt forming a layer 14 on at least one side. Imbedded in the layer 14 is a granular material 16 which may desirably be slate of a brick color, such as red. Painted or printed over the layer 16 is a coating of asphalt 18 which forms a design as shown in Figure 2. The asphalt of the design 18 is surfaced with a differently colored granular material 19 which may be finely crushed slag. The asphalt coating 18 is not merely applied only to the granular layer 16, but also penetrates and fuses to the layer 14 of asphalt.

75

As illustrated clearly in Figure 2 the design may desirably comprise the outlines of two rows of bricks, or speaking more exactly, it may comprise the area which would normally constitute the spaces between and around the bricks in two rows. The design also includes the projections or markers 20 which extend above the second row of imitation bricks in the position of the vertical spacing for a third row of bricks. These markers 20 are very useful in laying the strips on a wall. Of course any other number of rows of bricks may be simulated if desired, and the proportions of the strips may be changed. One advantage of this manner of cutting is that the length of the strips is not limited to the width of the web. By making the strips longer, fewer need be laid.

80

As illustrated clearly in Figure 2 the design may desirably comprise the outlines of two rows of bricks, or speaking more exactly, it may comprise the area which would normally constitute the spaces between and around the bricks in two rows. The design also includes the projections or markers 20 which extend above the second row of imitation bricks in the position of the vertical spacing for a third row of bricks. These markers 20 are very useful in laying the strips on a wall. Of course any other number of rows of bricks may be simulated if desired, and the proportions of the strips may be changed. One advantage of this manner of cutting is that the length of the strips is not limited to the width of the web. By making the strips longer, fewer need be laid.

85

The strips are laid as shown in Figure 4, with first a bottom row and then with each succeeding row covering the upper line of the design and laid with its righthand end just meeting one of the markers 20 of the row beneath. This results in having the brick images of the upper strip properly staggered with relation to the brick images of the lower strip.

90

It is obviously desirable that the edges of the strip exactly coincide with the intended edges of

110

the design. To accomplish this result the trans-
verse cuts 22 are first made in the web at the time
of printing after the initial surfacing, and in fact
with the printing roller, so that there is no chance
5 of the cuts not being in the right position with
respect to the design. As shown in Figure 1 these
cuts are arranged in staggered relation and each
cut is preferably interrupted at its center so that
the web may be drawn along in the usual manner
10 as if not cut. After the material has again been
surfaced and cooled, the longitudinal slitting
along the dotted line 24 is performed in the usual
way, there being no difficulty in properly aligning
the longitudinal cuts.

15 The above described process for manufacturing
and cutting these strips is more fully disclosed
and is claimed in my co-pending application
Serial Number 511,696, filed January 28th, 1931,
entitled Process and apparatus for making build-
20 ing strips.

It is to be understood that many other em-
bodyments of the invention, including some in
improved form, will be apparent, and in the course
25 of time more will be devised by those skilled in
the art. It is not desired that this invention be
limited to the details described, for its scope in-
cludes all such forms or improvements as come
within the spirit of the following claims, con-
30 strued as broadly as the prior art will permit.
Especially it should be realized that as to some
aspects of the invention any desired design may
be used and that the particular colors used are
utterly immaterial so long as there is a contrast.

What is claimed is:

35 1. Artificial brick and mortar simulating siding,
including: a plurality of overlapping strips; each
comprising a saturated and coated base com-
pletely covered on one side with a brick simulat-
ing granular surfacing material, which latter is
40 covered with a granulated surfacing material of
contrasting color adhered thereto along a design
simulating mortar joining the bricks by an ad-
hesive layer; each strip being of uniform contour

free of weakening indentations; and being under-
lapped through part of its height by the strip
therebelow and being overlapped through approx-
imately the rest of its height only by the strip
thereabove to provide uniform two-thickness
80 coverage, the design on each shingle being ex-
tended into the overlap region to provide markers
for both vertical and lateral positioning of verti-
cal and horizontal edges of the shingles relative
to each other.

2. A building strip comprising: a suitable base,
a granular surfacing layer extending over the
entire base, and a design formed on said layer;
said design comprising a layer of adhesive mate-
rial on said first surfacing layer and a surfacing
therefor of a color contrasting the color of the
first named surface; said design representing the
90 spaces between and surrounding bricks, the lower
half of the strip including the simulation of the
same number of horizontal spacing lines as of
horizontal brick rows, and the upper half includ-
ing a vertically extending portion of the design
95 which is arranged as a guide for staggering the
strips and for that purpose is located at a pos-
ition coinciding with the vertical edge of a prop-
erly staggered strip.

3. Artificial brick and mortar simulating siding
including: a plurality of overlapping strips; each
comprising a saturated and coated base com-
pletely covered on one side with a brick simulat-
ing granular surfacing material, which latter is
105 covered with a granulated surfacing material of
contrasting color adhered thereto along a design
simulating mortar joining the bricks by an ad-
hesive layer; each strip being of uniform contour
110 free of weakening indentations; and being under-
lapped through part of its height by the strip
therebelow and being overlapped through approx-
imately the rest of its height only, by the strip
thereabove to provide uniform two-thickness
115 coverage.
